UNITED STATES PATENT OFFICE.

WILLIAM F. MARTIN, OF KENOSHA, WISCONSIN.

SHOE-CLEANER.

1,179,541.

Specification of Letters Patent. Patented Apr. 18, 1916.

Application filed July 31, 1914. Serial No. 854,220.

To all whom it may concern:

Be it known that I, WILLIAM F. MARTIN, a citizen of the United States, and resident of Kenosha, in the county of Kenosha and State of Wisconsin, have invented new and useful Improvements in Shoe-Cleaners, of which the following is a description, reference being had to the accompanying drawings, which are a part of this specification.

This invention relates to improvements in shoe cleaners and more particularly to that type for cleaning the soles and sides of boots and shoes.

It is one of the objects of the present invention to provide a shoe cleaner whereby the sides of the boot or shoe are cleaned while the sole is being moved back and forth over the scraper portion of the device.

A further object of the invention is to provide a shoe cleaner which may be formed from a single piece of sheet metal and without any waste thereof.

A further object of the invention is to provide a shoe cleaner formed of sheet metal in which the parts thereof are bent to form and are then locked in position by other parts of the sheet metal.

With the above and other objects in view, the invention consists of the improved shoe cleaner and its parts and combinations as set forth in the claims, and all equivalents thereof.

In the accompanying drawing in which the same reference characters indicate the same parts in all of the views: Figure 1 is a side view of the improved shoe cleaner; Fig. 2 is a top view thereof; Fig. 3 is a transverse sectional view thereof taken on line 3—3 of Fig. 1; Fig. 4 is a similar view thereof taken on line 4—4 of the same figure; and Fig. 5 is a plan view of the blank before it has been bent into shape.

Referring to the drawing the numeral 8 indicates the blank or rectangular piece of metal which is provided with a U-shaped cut 9 to form a rectangular lip 10 and a U-shaped member 10' consisting of a bottom portion 11 and side or stem portions 11'. Locking tongues 12 are also formed in the blank as well as corner apertures 13 to receive securing screws or nails (not shown). The side and bottom lines of the U-shape cut 9 are parallel to the side and bottom edges of the blank and approximately extend through one half portion thereof. The locking tongues 12 are formed in the uncut

half portion 14 of the blank and are located at opposite ends of the blank outside of the plane of the side cuts of the lip.

The stem portions 11' of the U-shaped part are bent to form upper circular alined tubes 15 and the bottom portion 11 is bent to rest against the side of the uncut part of the blank and is overlapped by the lip 10 which is bent to form the scraping edge 65 10" of the cleaner and extends downwardly and is curved outwardly to form one of the legs or base portions 16 of the cleaner. The uncut portion of the blank is also curved outwardly to form the other leg or base portion 17 of the cleaner.

The U-shaped member of the blank is held in formed position by means of the locking tongues 12 which are bent to overlap the bottom portion 11 of said member. 75 These tongues also serve as a support for said U-shaped member. The circular tubes 15 form sockets for the shanks of brushes 18 mounted therein and the said tubes are flattened slightly to hold the brushes in said 80 tubes. The brushes extend inwardly toward each other and are adapted to be engaged by the side portions of a boot or shoe scraped over the edge 10" of the cleaner.

In use, a person places the sole of the shoe 85 on the scraping edge of the device and by drawing the foot back and forth over the scraping edge, mud and dirt are readily taken off the sole and at the same time the side brushes clean the sides of the shoe. If 90 the shoe is narrower than the space between the brushes, the foot can, of course, be moved laterally into engagement with either brush.

From the foregoing description it will be seen that the shoe cleaner is of very simple 95 construction, is strong and durable and is well adapted for the purpose described.

What I claim as my invention is:

1. A shoe cleaner, comprising a sheet metal blank having a U-shaped cut to form 100 a lip and a U-shaped portion, the side parts of the U-shaped portion being bent to form brush holding tubes and the lip being bent to form a scraping edge and overlapping the bottom part of the U-shaped portion and 105 being curved outwardly to form a supporting leg, another portion of the blank also being curved outwardly to form the other supporting leg, and brushes inserted into the holding tubes.

2. A shoe cleaner, comprising a sheet metal blank having a U-shaped cut in ap-

proximately one-half portion to form a lip and a U-shaped portion, the side parts of the U-shaped portion being curved to form brush holding tubes and the lip being bent 5 to form a scraping edge and overlapping the bottom part of the U-shaped portion and extending downwardly and outwardly to form a supporting leg, the uncut half portion of the blank also extending downwardly and 10 outwardly to form the other supporting leg, portions of the uncut half portion of the blank being cut to form tongues for engaging and locking the bottom portion of the U-shaped part in position, and brushes inserted in the holding tubes and extending 15 toward each other.

3. A shoe cleaner formed of an integral sheet metal blank having a U-shaped cut half portion to form a lip and a U-shaped portion, the lip being bent, longitudinally of its length to form a scraping edge and to extend the lip downwardly to form a supporting leg, the uncut half portion of the blank also extending downwardly and outwardly to form the other leg, the bottom portion of the U-shaped part extending between the lip and the uncut half portion adjacent to the longitudinal bend of the lip and the side parts of the U-shaped portion 20 extending upwardly above the plane of the bent part and being bent to form brush holding tubes, portions of the uncut half portion of the blank being cut to form projecting tongues which overlap the bottom portion 25

35 tion of the U-shaped part and lock it in position, said blank also having apertures for receiving means for securing the device to a support, and brushes mounted within the holding tubes and extending toward each other.

4. A shoe cleaner formed of an integral sheet metal blank having a U-shaped cut half portion to form a lip and a U-shaped portion, the lip being bent longitudinally of its length to form a scraping edge and to 40 extend the lip downwardly to form a supporting leg, the uncut half portion of the blank also extending downwardly and outwardly to form the other leg, the bottom portion of the U-shaped part extending between the lip and the uncut half portion 45 close to the longitudinal bend of the lip and the side parts of the U-shaped portion extending upwardly above the plane of the bent part, portions of the uncut half portion of the blank being cut to form projecting tongues which overlap the bottom portion 50 of the U-shaped part and lock it in position, said blank also having apertures for receiving means for securing the device 55 to a support.

In testimony whereof, I affix my signature, in presence of two witnesses.

WILLIAM F. MARTIN.
